UNITED STATES PATENT OFFICE.

MARK W. HARRIS, OF COLUMBUS, GEORGIA.

FIRE-DOOR.

1,102,047.

Specification of Letters Patent. Patented June 30, 1914.

Application filed March 21, 1913. Serial No. 755,963.

To all whom it may concern:

Be it known that I, MARK W. HARRIS, a citizen of the United States, residing at Columbus, in the county of Muscogee and State of Georgia, have invented new and useful Improvements in Fire-Doors, of which the following is a specification.

This invention relates to fire-doors, for use in connection with furnaces of all kinds, 10 the fire-door hereinafter described being especially designed for use upon the furnaces of locomotive boilers, in order to enable the door to be easily opened and closed for each shovel of fuel fed to the furnace, thereby 15 rendering it possible to maintain the steam pressure of the boiler, which, as is well understood, is interfered with seriously when the fuel door is allowed to remain open for any considerable period of time.

20 A further object of the invention is to provide a fuel door which embodies the utmost simplicity of construction and operation, which may be produced at a comparatively low original cost, which may be maintained in operative condition at a minimum expense, the door being constructed in such manner and combined with such operative mechanism that it may be operated by downward pressure of the foot of the stoker, the 25 door automatically returning to its closed position without any attention whatever on the part of the stoker.

With the above and other objects in view, the invention consists in the construction, 30 combination and arrangement of parts, as will be hereinafter more fully described, illustrated in the accompanying drawings, and pointed out in the claim hereunto appended.

40 In the drawing Figure 1 is a front elevation of the fire-door of this invention shown closed. Fig. 2 is a similar view, showing the door open. Fig. 3 is a side elevation thereof, showing the foot controlled 45 door operating mechanism. Fig. 4 is a vertical section taken centrally through the door and its frame. Fig. 5 is a horizontal section taken through the lintel.

Referring to the drawings, 1 designates 50 the front wall of a furnace, the same being provided with a fuel door opening 2, which may be of any desired size and shape. Arranged at opposite sides of the fuel door and fastened to the outer face 55 of the wall of the furnace are ver-

tically extending parallel guides 3 having secured to their inner faces parallel guiding strips 4, between which the opposite vertical edges of the fuel door 5 slide. Between the inner set of guiding strips and the 60 front face of the furnace wall, facing segments 6 are inserted, so as to form a convenient bearing for the inner side of the fuel door 5, thereby effectively excluding chilling blasts.

65 The door 5, in the preferred embodiment of this invention, consists of a front plate, and a back plate, as shown, said plates being spaced apart to leave an intervening air circulating space, and the front and back 70 plates of the door being fixedly connected together by an interposed batten 7. Connected pivotally to the top of the door, at the point 8, is an upwardly extending pivotal and swinging link 9, the upper extremity of which is pivotally connected, at 10, to the inwardly extending arm 11 of a two-arm lever, the outer arm 12 of which has attached to its extremity a door counterbalancing weight 13. The two-armed lever, 75 which constitutes a door counterbalancing lever, is fulcrumed, at 14, on a post 15 extending upwardly from one of the guides, above described.

80 The oppositely arranged guides are connected at a point above the door opening by means of a lintel 16 which forms a support for the fulcrum pin or bolt 17 of a transmission lever 18, the same being centrally fulcrumed on said bolt, as shown. 90 Pivots connected to one arm of said transmission lever is a link 19 which extends upwardly to the counterbalancing lever and is pivotally connected thereto, at 20. Pivotally connected, at 21, to the opposite end 95 of the transmission lever is a pivotal link 22 extending downwardly and being pivotally connected, at 23, to the inner end of a foot lever 24 provided at its forward end with a treadle 25. The lever 24 is pivotally mounted, at 26, on a short post 27 which extends upwardly from the floor of the cab or room in which the fuel door is mounted.

100 Arranged beneath the door 5 is a door sill 28 having an inclined and downwardly sloping inner face 29, which is arranged in spaced relation to the front wall of the furnace, so that any particles of coal or ashes which may fall upon the sill will be carried, by gravity, down the sloping inner face of 110

said sill, thereby keeping the upper surface of the sill clear of such obstructing material, and insuring the proper closing of the door, preventing any draft from passing under the bottom edge of the door, through the door opening and into the furnace.

In operation, the fireman needs only to press downwardly on the projecting end of 10 the foot lever, whereupon the door which is nicely counterbalanced is moved upwardly, allowing a shovel of coal to be thrown into the furnace. As soon as the foot lever is released, the door automatically closes by 15 reason of a preponderance of weight over that at the outer extremity of the counterbalancing lever. On account of the simplicity of the construction involved, there is very little liability of the operating mechanism getting out of order, but in such a 20 contingency, the necessary adjustment or repair may be easily effected by the engineer or fireman in a short space of time, which will preclude a chilling of the fire

and consequent reduction in the steam pressure. 25

What is claimed is:

In a fire door structure, the combination with the front wall of a fire box, of parallel vertical guides fastened thereto at opposite 30 sides of the fuel door opening, a lintel rigidly connecting said guides above the fuel door opening, a door slideable vertically between said lintel and the front wall of the fire box, a weighted door counterbalancing 35 lever connected at one end with the door, a foot controlled lever arranged at one side of the door frame, and a transmission lever fulcrumed centrally of the door lintel and connected at one end with the foot lever and 40 at the other end with the door counterbalancing lever.

In testimony whereof I affix my signature in presence of two witnesses.

MARK W. HARRIS.
